Primary Examiner — John R Yeh(74) *Attorney, Agent, or Firm* — Craig M. Bohlken(57) **CLAIM**

The ornamental design for a cleaning wipe, as shown and described.

DESCRIPTION

The sole FIGURE is a top plan view of a cleaning wipe showing our new design.

The claim is limited to the elements shown in solid lines. The dot-dash lines shown along the perimeter of the FIGURE depict the boundaries of the cleaning wipe and form no part of the claimed design.

1 Claim, 1 Drawing Sheet(56)
